(57) **CLAIM**

The ornamental design for a mounting device, as shown and described.

DESCRIPTION

FIG. 1 is a top right perspective view showing a mounting device according to the invention;

FIG. 2 is a left or right side elevational view showing the mounting device of FIG. 1;

FIG. 3 is a front elevational view showing the mounting device of FIG. 1;

FIG. 4 is a top plan view showing the mounting device of FIG. 1;

FIG. 5 is a bottom plan view showing the mounting device of FIG. 1; and,

FIG. 6 is a bottom right perspective view showing the mounting device of FIG. 1.

In FIGS. 1-6, the broken lines represent at least one of the following features: a ball or sphere and a neck or extension connecting the ball to the mount, and respectively, these identified features form no part of the claimed design.
